[57] CLAIM

The ornamental design for a tissue box holder, as shown and described.

DESCRIPTION

FIG. 1 is an end view of the tissue box holder with the holder folded against the tissue box showing my new design;

FIG. 2 is a side view of the invention thereof;

FIG. 3 is a side view opposite FIG. 2 thereof;

FIG. 4 is an end view opposite FIG. 1 thereof;

FIG. 5 is a plan view with the holder unfolded from the tissue box thereof;

FIG. 6 is a perspective view of the invention showing my new design with a broken line view of a mattress and box spring having the tissue box holder inserted between them for illustrative purposes only and forms no part of the claimed design; and,

FIG. 7 is a plan view of the tissue box holder unfolded.
